Isaac Mershon, Brooklyn, N. Y., assignor to Globe Silver Co., Inc., New York, N. Y., a corporation of New York

Application October 9, 1956, Serial No. 43,274

Term of patent 14 years

(Cl. D29—20)

Fig. 1

Fig. 2

Fig. 1 is a front elevational view of a frame for a picture or similar article showing my new design, the ornamentation in the right half being symmetrically disposed with that in the left half.

Fig. 2 is an end elevational view thereof, the right half being symmetrically disposed with the left half.

The dominant features of my design reside in the portions shown in full lines.

I claim:

The ornamental design for a frame for a picture or similar article, as shown and described.
